SOUND PRODUCING TOY

Norman M. Epstein, 835 S. Holt St., Los Angeles, Calif.

Filed Dec. 7, 1964, Ser. No. 82,937

Term of patent 14 years

(Cl. D34—15)

FIGURE 1 is a perspective view of a sound producing toy showing my new design.

FIGURE 2 is a front elevational view of the said toy.

FIGURE 3 is a side elevational view of the said toy, partly broken away showing the exterior portion of the sound element contained within the said toy.

FIGURE 4 is a back elevational view of the said toy.

I claim:

The ornamental design for a sound producing toy, substantially as shown.
